BOOK OR SHEET HOLDER

Earl T. Ryang, Chicago, Ill.

Application November 25, 1935, Serial No. 51,444

10 Claims. (Cl. 45—121)

This invention relates to sheet and book-holding racks, particularly such as are used for holding copy for typewriters, or as music racks.

The main objects of this invention are to provide an improved form of copyholding rack which is foldable into compact form and capable of being readily set up or folded by a few simple operations; to provide a sheet-holding rack comprising a plurality of narrow bars secured in skeleton frame relation so as to form a substantial backing for supporting a copy sheet and adapted to be swung relatively to each other so that all the parts may lie one against the other in a compact assembly; and to provide a standard of improved form and arrangement to support the rack effectively in use and contractible to a length but little greater than the width of the copyholding rack and adapted to serve as a housing for the rack in its folded position.

20 These objects are accomplished by the device shown in the accompanying drawings in which:

Figure 1 is a perspective view of a copyholder constructed according to my invention and particularly designed as a typewriter copyholder.

25 Fig. 2 is a vertical section taken on the central plane of the standard and rack with the parts occupying substantially the same position in which they are illustrated in Figure 1.

Fig. 3 is a detail in plan of the upper end of 30 the standard in a position corresponding to that of Fig. 2.

Fig. 4 is a fragmentary rear view of the rack in a partly folded position.

Fig. 5 is a top view of the rack in its completely folded position.

Fig. 6 is a front view of the standard.

Fig. 7 is a detail of the lower end of the standard.

Fig. 8 is a fragmentary bottom view of the base structure when the parts are in the position shown in Fig. 6.

Fig. 9 is a sectional detail taken at the end of the main beam of the copy-holding rack on the line 9—9 of Fig. 4.

45 Fig. 10 is a detail of the joint between the cross arms at the middle of the copyholding rack.

Fig. 11 is a front view of the standard illustrating its appearance when contracted and closed with the rack housed within it in the compact portable form in which the device appears when ready for storage or shipment.

While the device shown has a considerable range of utility, it is particularly designed for compact storage; as for example, in a form suit-

able for use in connection with a portable typewriter.

In the forms shown, the standard comprises a main member 1 of rectangular cross section and of tubular or channel form, within which is telescopically slidable a second channel-shaped member 2.

In the forms shown, the member 1 is open at the front side and provided with inwardly facing front flanges 3 which overlap the front edges of the side portions of the member 2, so as to confine the latter telescopically within the member 1. At the upper end of the member 1, a pivoted dog 4 has pawl portions 5 that engage notches 6 in the member 2 for locking the latter in various positions of adjustment. The dog is provided with a spring 7 that holds the pawls in engagement with the member 2 and has a tail 8 which may be depressed to lift the pawls out of their notches 6.

A third channel shaped member 9, preferably of the same transverse form as the member 2, is pivotally connected to the upper end of the member 2 and is swingable between a position of alignment with the member 2 and the inclined position in which it is shown in Figures 1 and 2.

A pair of pawls 10 pivoted on opposite sides of the member 9 engages notches 11 and 12 in a head 13 of the member 2 for securing this member 9 in either of these two limiting positions. The pawls 10 are preferably mounted on the squared ends of the pivot pin 14 so that they swing in unison with each other. Pins 15 are limit stops for the movement of the pawls 10.

Fitted within the lower end of the member 1 of the standard is a heel block 16 which has a pivot pin 17 whose projecting ends are seated in slots 18 in the side flanges of the member 1, so that said heel block may be moved from the position in which it is shown in Figure 2 to a position 40 for closing the end of the member 1, as is illustrated in Figures 1, 2, 6 and 7.

The member 1 of the standard is supported in the vertical position in which it is shown in Figures 1 and 2 by means of a pair of foot bars 19 which are secured to the bottom end of the heel block 16 by pivots 20 (Fig. 8) and these foot bars are movable between the spread position, shown in Fig. 1, and the side-by-side position in which they are shown in Fig. 8.

A pivoted latch member 21 locks these foot bars 19 in their spread position. This latch is provided with shoulders 22 which extend into grooves 23 in the inside faces of the adjacent portions of the bars 19 and hold the lower end of the standard 55

firmly against the bars 19 as well as keeping those bars spread apart. This latch member 21 may be swung upwardly 180° in its released position as shown in Figure 7, and the heel block 16 may then be slid down along the slot 18 so that the bars 19 may be brought together and laid along the open face of the channel member 1 to close said face when the parts are in their housed position.

The upper end of the standard member 9 is closed by means of a head block 25 which has seats 26 for receiving the arms 27 that carry the rack or copyholder frame. The adjacent ends of these arms 27 are oppositely mortised and interlocked in crossed relation as may be seen in Figures 1, 2 and 3 and are seated in these grooves 26 by dropping them downwardly from the top and then locking them in that position by means of a pivoted button 28. In Fig. 3 this button is shown in full lines in the position which it occupies to admit the arms 27 into the grooves 26. It may be turned to the position in which it is shown in Fig. 2 in which it rigidly locks these arms in place on the standard.

The copyholder or sheet rack comprises a main horizontal beam 30 upon which are mounted at its middle point the crossed diagonal bars 31.

The diagonal bars 31 are mounted in scissors relation on the pivot 32. Traveler blocks 33 are mounted on the outer ends of the beam 30 to slide along the slots 34 and each of these traveler blocks carries a pair of toggle arms 35 and 36 which are pivoted to each other and the block 33 by a pin 37. The toggle arms 35 and 36 are also pivoted at their outer ends to the bars 31 at 35.1 and 36.1 respectively, in such manner that when the traveler blocks 33 occupy their innermost positions, the bars 31 will be spread to their expanded position and when the traveler blocks occupy the outer limits of their travel, the bars 31 will be brought together so as to lie along the beam 30, this relationship being further illustrated in Fig. 4.

The forward ends of the arms 27 are hinged to the traveler blocks 33 as shown in Figure 4 and are arranged to be folded flat against the rear face of the beam 30 when the travelers are at their extreme position and to be held in such folded position by the ends of the yoke 46, as shown in Figure 5. If desired, the traveler blocks can be secured against accidental shifting out of this extreme position by having projecting pins 39.1 positioned on the bar 30 so as to enter apertures 27.2 in the arms 27 when the parts are in this position.

The bars 36 have swingable arms 38 pivoted at 39 at their lower ends which serve as ledge elements to support a sheet or book resting against the rack.

The same pivot 32 that carries the bars 31 has mounted thereon a vertical cross bar 40. The bar 40 has pivoted at its lower end a ledge element 41 in horizontal alignment with the ledge elements 38 when the parts are in the position shown in Fig. 1.

At the upper end of bar 40, there is a clamp 42 pivoted at 43 having an arm 44 by means of which it is swung to its open position and having spring 45 which normally closes the clamp.

A yoke-like bar 46 is fixedly mounted on the rear end of the pivot 32 so as to swing in unison with the bar 40. This yoke 46 is provided with shoulders that cooperate with pins 46.1 and 46.2 for limiting the movement of the bar 40 and with a latch member 47 which secures the bar 40 in each of its two limiting positions; namely, in the upstanding position in which they are shown in

Fig. 4 and a position of parallelism with the main beam 30. The bars 40 and 46 are secured in fixed relation to each other as by squaring the adjacent portions of the pivot 32 or otherwise fixing these bars on the pivot.

Each end of the beam 30 is provided with a transversely slotted head 50 in which a hinge blade 51 is pivoted. Spring pointer arms 52 are pivotally mounted on the blades 51 in such a manner as to bear against and swing along the plane of the copy that might be mounted on the rack and the blades 51 may also be swung upwardly to carry the pointer arms 52 around the beam 40 so that they may occupy the position in which these arms are shown in Fig. 5, when the rack is completely folded.

The operation of the device shown is as follows:

In the compact form which the device presents when folded, as shown in Fig. 11, it is about the same length as a typewriter frame and may accordingly be readily stored in a compartment in a case that might be designed for carrying the typewriter.

To set up the device, the foot bars 19 which form the closure for the housing are swung down on the pivot 17 so as to open the front of the housing and the folded rack may then be readily withdrawn. The foot bars are then swung apart to the position in which they are shown in Figure 1. The heel block 16 is pushed into the member 1 until the latter rests on the foot bars and the latch member 21 is then swung down to fix the foot bars in their spread position. The upper section 9 of the standard is then tilted forward and latched in this position by the pawls 10.

To spread open the rack frame, the page-holder spring arms 52 are swung to the front side of the rack on their blades 51. Then the latch 47 is released and the vertical cross bar 40 is swung to its transverse position with respect to the main beam where it is locked by the latch 47.

The turning of the vertical bar carries with it the yoke bar 46 because of the fact that these bars are fast on the same pivot. This releases the ends of the arms 27 which are then grasped by the hands of the operator and employed to shift the travelers 33 to their innermost positions, causing the toggle arms to spread the crossed bars 31. The rearward ends of the arms 27 are now interlocked in their mortises 27.1 and seated in the grooves 26 where they are secured by turning the button 28 at the upper end of the standard to its locking position, as indicated by arrow 28.1 in Fig. 3 where it is shown in its off position, 180° from the locking position.

The ledge members 38 and 41 are now turned down and the device is ready for use.

The standard is adjustable vertically by releasing the spring-pressed dog 4 from engagement with the member 2 and sliding that member to any desired position. It is to be noted that the foot bars lie flat upon the surface upon which the device rests and are, therefore, appropriately located to permit a typewriter to be set over them so as to afford additional anchorage for the structure. It is also to be noted that the forward tilt of the standard allows the arms 27 to be comparatively short, so that they stand at a wide angle to each other with the weight of the rack and its contents located substantially over the center of area of the triangle that is defined by the foot bars 19.

The spring arms 52 being swingable in a vertical plane about their axes serve not only to hold the copy sheet securely against the rack or to

hold open the pages of a book or pamphlet that might rest on the rack, but they also can be employed to indicate the particular lines that are being copied.

5 Although but one specific embodiment of this invention is herein shown and described, it is to be understood that details as set forth may be altered or omitted without departing from the spirit of the invention as defined by the following claims.

I claim:

1. In a device of the class described, a rack comprising a horizontal beam, a pair of diagonal bars pivotally mounted on said beam, a pair of travelers respectively mounted at opposite ends of said beam and longitudinally slidable thereon, two pairs of toggle-jointed spreader arms having their joints respectively pivoted to said travelers and having their ends pivoted to said diagonal bars, a pair of rearwardly extending arms respectively connected to said travelers, said rearwardly extending arms being swingable into and out of the plane of said rack and being adapted to interlock with each other in their rearwardly extended position.

15 2. In a device of the class described, a rack comprising a horizontal beam, a pair of diagonal bars pivotally mounted on said beam, a pair of travelers respectively mounted at opposite ends of said beam and longitudinally slidable thereon, two pairs of toggle-jointed spreader arms having their joints respectively pivoted to said travelers and having their ends pivoted to said diagonal bars.

20 3. In a device of the class described, a rack comprising a horizontal beam, a pair of diagonal bars pivotally mounted on said beam, a pair of travelers respectively mounted at opposite ends of said beam and longitudinally slidable thereon, two pairs of toggle-jointed spreader arms having their joints respectively pivoted to said travelers and having their ends pivoted to said diagonal bars.

25 4. In a device of the class described, a rack comprising a horizontal beam, a pair of diagonal bars pivotally mounted on said beam, a pair of travelers respectively mounted at opposite ends of said beam and longitudinally slidable thereon, two pairs of toggle-jointed spreader arms having their joints respectively pivoted to said travelers and having their ends pivoted to said diagonal bars, and a vertical cross bar pivoted at its medial point on said horizontal beam to swing into parallelism therewith.

30 5. In a device of the class described, a rack comprising a horizontal beam, a pair of diagonal bars pivotally mounted on said beam, a pair of travelers respectively mounted at opposite ends of said beam and longitudinally slidable thereon, two pairs of toggle-jointed spreader arms having their joints respectively pivoted to said travelers and having their ends pivoted to said diagonal bars, a vertical cross bar pivoted at its medial point on said horizontal beam to swing into parallelism therewith, and means for locking said vertical cross bar in its vertical position.

35 6. In a device of the class described, a rack comprising a horizontal beam, a pair of diagonal bars pivotally mounted on said beam, a pair of travelers respectively mounted at opposite ends of said beam and longitudinally slidable thereon, two pairs of toggle-jointed spreader arms having their joints respectively pivoted to said travelers and having their ends pivoted to said diagonal bars, a vertical cross bar pivoted at its medial point on said horizontal beam to swing into parallelism therewith, and retractible ledge means on the lower ends of said vertical cross bar and spreader arms.

6. In a device of the class described, a rack comprising a horizontal beam, a pair of diagonal bars pivotally mounted on said beam, a pair of travelers respectively mounted at opposite ends of said beam and longitudinally slidable thereon, two pairs of toggle-jointed spreader arms having their joints respectively pivoted to said travelers and having their ends pivoted to said diagonal bars, a pair of rearwardly extending arms respectively connected to said travelers, said rearwardly extending arms being swingable into and out of the plane of said rack and being adapted to interlock with each other in their rearwardly extended position.

10 7. In a device of the class described, a rack comprising a horizontal beam, a pair of diagonal bars pivotally mounted on said beam, a pair of travelers respectively mounted at opposite ends of said beam and longitudinally slidable thereon, two pairs of toggle-jointed spreader arms having their joints respectively pivoted to said travelers and having their ends pivoted to said diagonal bars, a pair of rearwardly extending arms respectively connected to said travelers, said rearwardly extending arms being swingable into and out of the plane of said rack and having their rearward end portions oppositely mortised for interlocking in crossed relation in their rearwardly extended position.

15 8. In a device of the class described, a rack comprising a horizontal beam, a pair of diagonal bars pivotally mounted on said beam, a pair of travelers respectively mounted at opposite ends of said beam and longitudinally slidable thereon, two pairs of toggle-jointed spreader arms having their joints respectively pivoted to said travelers and having their ends pivoted to said diagonal bars, a pair of rearwardly extending arms respectively connected to said travelers, said rearwardly extending arms being swingable into and out of the plane of said rack and being adapted to interlock with each other in their rearwardly extended position, a standard having at its top a seat for the interlocked ends of said rearwardly extending arms, and means for securing said arms in said seat.

20 9. In a device of the class described, a standard comprising a pair of telescoping channel bars, means for securing said channel bars in adjustable longitudinal relation to each other, a base comprising a pair of bars connected to one of said channels and swingable toward and away from each other in a horizontal plane, means for locking said bars in fixed relation to said standard when occupying such angular position, and each of said bars being also swingable so as to lie along said channels to close the open side thereof when said bars are released from said locking means.

25 10. A device of the class described, comprising telescopically interfitting hollow standard members, one having a base formed of angularly disposed foot bars, foldable to lie along said one standard member and another said standard member having an extension tiltably mounted at its upper end, a head on said extension, and a foldable sheet-rack carried by said head.

EARL T. RYANG.
